GELATIN DESSERT FORMING MACHINE

Charles T. Walter and Joseph Bech, Chicago, Ill.,
assignors to Swift and Company, Chicago, Ill.,
a corporation of Illinois

Application June 20, 1932, Serial No. 618,178

15 Claims. (Cl. 107—17)

The invention relates to an automatic machine for the manufacture of gelatin dessert cakes.

Heretofore gelatin dessert cakes have been made by hand operated sheet metal forms. The apparatus and process are expensive from the labor standpoint; are wasteful of material and do not give well shaped uniform cakes.

The object of the present invention is to provide a commercial, practical and comparatively inexpensive automatic gelatin dessert cake machine of strong, durable construction adapted to eliminate expensive and wasteful hand operated apparatus and capable of operating on a continuous cycle at a relatively high rate of speed and of producing uniform well shaped cakes of gelatin dessert of standard shape and of surface condition far superior to the hand made cakes.

A further object of the invention is to feed the material automatically to the machine and automatically from the machine and thereby eliminate the labor of manually handling the product after discharge from the machine.

Also it is an object of the invention to provide an automatic gelatin dessert machine which will have very small clearance between the adjacent moving parts of the forming dies and which will not require lubrication of such parts and at the same time, be free from distortion during heat treatment and have reasonable resistance to corrosion.

The machine of the present invention may be used in the production of gelatin tablets of the character described in the claims of the copending applications of Clarence C. Zeigler, Serial No. 427,651, filed February 11, 1930, and Serial No. 456,827, filed May 28, 1930. The material as it is fed to the machine for compression into tablets may be described as a friable powder, the material being a slightly moist mixture of sugar, gelatin, coloring, flavoring, and the like.

With these and other objects in view, the invention consists in the construction and novel combination and arrangement of parts herein-after fully described, illustrated in the accompanying drawings and pointed out in the claims hereto appended, it being understood that various changes in the form, proportion and minor details of construction, within the scope of the claims, may be resorted to without departing from the spirit or sacrificing any of the advantages of the invention.

In the drawings:—

Figure 1 is an elevation of an automatic gelatin dessert machine associated with the means

for automatically handling the product after discharge from the machine.

Fig. 2 is a detail view of the agitator of the hopper.

Fig. 3 is a plan view of the automatic gelatin dessert machine and the mechanism for handling the product discharged from the machine. 5

Fig. 4 is a detail vertical sectional view taken substantially on the line 4—4 of Fig. 3.

Fig. 5 is an enlarged detail view of the gearing 10 for operating synchronously the conveyor and the feeding means for delivering the aluminum strips from the magazine to the conveyor.

Fig. 6 is an enlarged detail transverse sectional view of the conveyor and a portion of the magazine. 15

Fig. 7 is a detail longitudinal sectional view of the same.

Fig. 8 is a detail horizontal sectional view on the line 8—8 of Fig. 7. 20

Fig. 9 is an elevation partly in section of the automatic gelatin dessert machine.

Fig. 10 is a plan view of the same partly broken away.

Fig. 11 is a detail horizontal sectional view on the line 11—11 of Fig. 13.

Fig. 12 is a detail view of the cleaning device.

Fig. 13 is a central vertical sectional view of the automatic gelatin dessert machine.

Fig. 14 is a horizontal sectional view on the line 14—14 of Fig. 13. 30

Fig. 15 is an enlarged detail perspective view of one of the plungers.

Fig. 16 is an elevation of a portion of the automatic machine, parts being omitted to show the annular cam groove. 35

Fig. 18 is a horizontal sectional view on the line 18—18 of Fig. 16.

Fig. 19 is an automatic view of the cam of the annular cam groove, the dotted lines showing the range of adjustment for this portion of the cam. 45

Fig. 20 is an enlarged perspective view of the ejector mechanism.

Fig. 21 is a side elevation of the same. 50

Fig. 22 is a similar view showing the other side of the ejector mechanism, parts being omitted.

Fig. 23 is a plan view of the ejector mechanism.

Fig. 24 is a horizontal sectional view of the same. 55

Fig. 25 is a detail perspective view of the cam and guides for controlling the ejector mechanism. Fig. 26 is a plan view of the same.

In the accompanying drawings in which is illustrated the preferred embodiment of the invention the gelatin dessert machine and the means for handling the product discharged from the machine are synchronously operated by an electric motor, but any other suitable motor or source of power may, of course, be employed, as will be readily understood.

The motor 1 which is mounted upon a foundation plate 2 is connected by chain gearing 3 with a longitudinal shaft 4 journaled in suitable bearings and connected by chain gearing 5 with a speed changer 6 located at the rear portion of the foundation plate 2 and having a transverse shaft 7 extending forwardly to the front portion of the foundation slab, as clearly illustrated in Fig. 3 of the drawings.

The speed changer shaft is connected by a chain gear 8 with a conveyor shaft 9 located at the inner end of an endless conveyor 10 and journaled in suitable bearings of a conveyor frame 11. The endless conveyor which may be of any desired construction and which consists of a series of links is arranged on sprocket wheels 12 and 13 located at the inner and outer ends of the endless conveyor and provided at intervals with strip engaging members 14 for carrying aluminum strips 15 from a magazine 16 to the gelatin dessert machine hereinafter fully described.

The conveyor frame may be of any desired construction and is preferably composed of side members 17 and top and bottom horizontal members 18 and 19, the top member forming a table or support for the upper flight of the endless conveyor and also for the aluminum strips when the same are carried beyond the magazine by the action of the conveyor. The strips which are preferably made of aluminum and which receive the cakes of gelatin dessert material, may, of course, be made of any suitable material and they are fed from the magazine one at a time along the top table portion 18 of the conveyor frame.

The aluminum strip which is positively engaged and actuated by flight means 14 mounted on the endless conveyor contacts with the strip previously fed from the magazine and the latter contacts with the strip in advance of it so that the strips are moved along the top member or table portion of the conveyor frame from one end of the same to the other end thereof by the action of the endless conveyor so that the strips will be carried from the magazine to the gelatin dessert machine and from the machine to the rear end of the table 18 where they are moved by hand and transferred to a drying tunnel. The gelatin dessert cakes when discharged from the gelatin machine are automatically transferred to the aluminum strips so that it is unnecessary to handle the product manually in transferring the finished product to the strips which form trays for the product.

The aluminum strips 15 are arranged in a stack within the magazine 16 and the said magazine is preferably formed by upright angle bars 20 located at the corners of the magazine and also forming supports for one end of the conveyor frame. The other end of the conveyor frame is supported by suitable posts 20a preferably of angle bar construction. The sides of the conveyor frame extend above the table member 18 at the side edges thereof and form a channel for the

aluminum strips, as clearly illustrated in Fig. 6 of the drawings. The aluminum strips consist of a horizontal top portion and vertical side portions provided at their lower edges with inwardly extending horizontal flanges 21 which are spaced apart, as clearly illustrated in Fig. 6 of the drawings, and the ends of the strips are provided with recesses 22 formed by cutting away the side portions and bottom flanges of the strips, as clearly shown in Fig. 7 of the drawings.

The terminal recesses 22 of the strips enable teeth of gear wheels 23 to engage the strips and feed the same downwardly within the magazine. The strip feeding gear wheels are located at the ends of the magazine at the bottom of the same and are preferably constructed of fiber, and in practice the rotary movement of the gear wheels 23 feed the strip by dropping the same two at a time upon the endless conveyor, as illustrated in Fig. 7 of the drawings. The strip engaging members 14 of the conveyor engage and feed the lowermost strip forwardly while the aluminum strip immediately above the one engaged by the endless conveyor is held against forward movement by a suitable stop 24 until the strip reaches the lowermost position and rests directly upon the endless conveyor.

The aluminum strip feeding gears of the magazine are mounted on short transverse shafts 25 journaled in suitable bearings of the corner uprights of the magazine and provided at their rear ends with beveled gears 26 which mesh with beveled gears 27 of a longitudinal shaft 28 located in rear of the magazine and extending the entire length of the same. The shaft 28 is connected by chain gear 29 with a smaller speed changer 30 which is connected by chain gearing 31 with the conveyor shaft 9. The speed changers 6 and 30 may be of any desired construction and adapted to control and regulate the speed of the endless conveyor and the magazine to synchronize the same with the gelatin dessert machine.

The longitudinal shaft 4 is connected by chain gearing 4a with a horizontal worm shaft 32 which operates the gelatin dessert machine and when the motor 1 is started, motion will be communicated to the gelatin dessert machine and the endless conveyor and the magazine will be synchronously operated.

The said speed changers 6 and 30 will synchronize the speed of the conveyor and the magazine with the speed of the gelatin dessert machine.

The stationary casing of the gelatin dessert machine comprises a hollow cylindrical base 33 and an upper cylindrical section 34 provided at its lower end with an outwardly extending horizontal flange 35 bolted or otherwise secured to the hollow base section 33 and forming a top wall for the same. The hollow base is bolted or otherwise secured to the foundation slab 2 and it forms a housing for worm gearing for rotating the rotary body portion 36 consisting of a vertical sleeve thickened at its upper portion and provided at the top with a horizontal plate 37 constituting the top of the rotary body portion of the machine. The rotary body portion is arranged on a stationary vertical post 38 which is circular in cross section and upper and lower ball bearings 39 and 40 are provided at the top and bottom of the rotary body portion 36 for enabling the said body portion 36 to rotate frictionlessly on the vertical post. The lower ball bearings 40 take the vertical thrust of the rotary body portion. The vertical post is stepped in a 75

flanged socket 38^a which is bolted through the bottom of the lower section of the casing to the foundation slab 2. The rotary body portion has fixed to its lower end a horizontal worm wheel 41 which meshes with the worm 42 of the said worm shaft 32. The worm 42 is located intermediate of the ends of the worm shaft and the latter is mounted in ball bearings 43 located at opposite sides of the lower section or base of the casing 10 of the machine at the front thereof, as clearly illustrated in Fig. 11 of the drawings.

The rotation of the worm shaft imparts rotary movement to the rotary body portion of the gelatin dessert machine. The plate 37 which constitutes the top of the rotary body portion of the gelatin dessert machine is circular and is equipped with an annular series of depending cylinders 44 arranged vertically and provided with rectangular bores 45 of oblong form in cross section receiving vertically movable plungers 46. The cylinders 44 which are preferably constructed separate from the rotary body portion have their upper ends arranged in openings 47 of the disk or plate 37 and are secured to the latter by any suitable means. The plungers 46 which extend downwardly below the lower ends of the cylinders 44 are equipped at their lower ends with horizontally disposed rollers 48 located at the inner sides of the plungers and arranged to operate in an annular cam groove 49 preferably formed by spaced upper and lower cam sleeves 50 and 51 presenting annular cam faces to the rollers of the plungers for effecting a positive vertical upward and downward movement of the plungers 35 during the rotary movement of the body portion of the machine. The upper and lower cam sleeves 50 and 51 are stationary and may be mounted on the upper section 34 of the casing in fixed relation with the same by any suitable means. The recession of the plungers downwardly within the bores 45 of the cylinders form compression chambers in which the loose pre-mixed material is fed from a substantially segmental mixing and feeding chamber 52 of a stationary casing 53 mounted upon the upper portion of the post 38 and located above and fitting a portion of the disk or plate 37 of the rotary body portion of the machine.

The casing 53 which forms the segmental mixing and feeding chamber 52 extends over approximately one-half of the plate 37 of the rotary body portion of the machine, as clearly illustrated in Fig. 14 of the drawings, and it has mounted therein a plurality of mixer shafts 54 having their upper portions mounted in ball bearings 55 and equipped at their lower ends with mixing blades 56 which stir the product and force the same into the compression chambers of the plate 37 and then smooth the top of the material 50 contained in the said compression chambers. The mixing blades 56 are set at a slight angle, as clearly illustrated in Fig. 13 of the drawings, so that they operate to pack the material in the compression chambers and simultaneously smooth the packed portions of the material. This will enable the material to be thoroughly mixed and at the same time will assure a substantially even amount of material being supplied to the compression chambers. The rotary body portion of 70 the machine is preferably equipped with six cylinders and the segmental casing 53 is preferably provided with four mixing shafts, but the number of cylinders and mixing shafts may, of course, be varied, as will be readily understood. The 75 mixing shafts are simultaneously rotated in the

same direction, as indicated by the arrows in Fig. 14 of the drawings, and they are connected with one another by chain drives 57 consisting of sprocket wheels mounted on the mixing shafts at the upper ends thereof and sprocket chains 5 arranged on the sprocket wheels and the mixing shaft at one end of the series is provided with a spur pinion 58 which meshes with a horizontal spur gear wheel 59 mounted on the upper end of a vertical shaft 60 journaled in suitable bearings 10 of the segmental casing 53 and provided at its lower end with a spur pinion 61 meshing with an internal gear 62 carried by the rotary body portion of the machine.

The internal gear 62 which surrounds the upper portion of the post 38 is suitably secured to the plate 37 of the rotating body portion of the machine and is arranged within a stationary gear cover 63. The gear cover 63 is enlarged at one side to form a bearing for the shaft 60 and when the plate 37 rotates, motion is transmitted to the mixing shafts through the said gearing which rotate in a clockwise direction while the rotary body portion of the machine rotates in a counterclockwise direction. The pre-mixed product is supplied to the mixing and feeding casing from an overhead hopper 64 preferably consisting of a cylindrical upper portion and a tapered lower portion which is connected with the substantially segmental feeding and mixing casing by means of a feed line 65 consisting of a pipe of sufficient diameter to permit the material to readily feed through the feed line by gravity and the feeding of the material from the overhead hopper is controlled by a valve plate 66 which controls the flow 30 of the product from the hopper into the feed line. The top of the segmental casing is provided with a plurality of product inlet openings 67 and a feed line 65 is shown in the central opening 67 in Fig. 3 of the drawings. The product receiving openings 40 67 will enable a plurality of overhead hoppers and feed lines to be connected with the feeding and mixing casing.

A mixing or agitating element 68 operates within the overhead hopper and conforms to the configuration of the same. The mixing and agitating element is mounted on a vertical shaft 69 journaled in suitable bearings carried by a frame or support 70. The agitator shaft 69 is connected with and actuated by an electric motor 71 suitably supported upon the framework 70 which may be of any desired construction.

As the product is released by the operation of the control plate or valve 66 it flows through the feed line into a mixing and receiving chamber. In the mixing and feeding chamber it is milled about by the revolving mixing blades which force the product into the compression chambers of the cylinders and completely fill the said compression chambers in the continuously rotating plate 37 directly beneath the feed or product inlet 65 into which the said feed line extends. The cake-shaped compression chamber is formed by the recession of the plunger to a different depth below the upper face of the plate 37. As one compression chamber is filled the rotation of the plate 37 which contains six of the compression chambers, causes the next compression chamber to be likewise filled and each of the compression chambers is successively filled as it is carried beneath the product receiving opening having the feed line discharging into it.

As the plate 37 revolves the plungers beneath the compression chambers which have been filled begin to rise due to the cam action so that 75

the cake is gradually raised above the upper face of the rotary plate 37 as the ejection point is approached. The vertical position of the respective plungers is controlled by the cam faces of the spaced upper and lower cam sleeves 50 and 51. As the rollers 48 run in the cam groove formed by the spaced upper and lower cam sleeves 50 and 51 the upward and downward movement of the plungers is positively controlled by the cam action of the said cam sleeves.

When the ejection position is reached the plunger thereat has raised the formed product cake so that the top surface of the plunger is on a level with the adjacent aluminum conveyor strip and in full side surface relation with the side of the aluminum strip and closely adjacent to the same. The cake is then quickly transferred to the moving aluminum strip by the action of the ejector mechanism hereinafter described.

Following the removal of the product cake from a plunger top the latter will be gradually lowered by cam action so that when a plunger has traveled about 36° around the periphery of the machine past the ejection point in a counter-clockwise direction its top has receded within the compression chamber to a clear level with the top surface of the plate 37. At this point there is located a metal scraper 72 for removing rough particles and just beyond the metal scraper is located a surface cleaning device 73 herein-after fully described.

After the surfaces of the rotating plate 37 about the compression chamber and the surface of the plunger top have been cleaned cam action causes the plunger to recede gradually below the surface of the rotating plate 37 so that the full size compression chamber is available by the time the filling point is again reached. This cycle of operation is continuously repeated while the machine is operated. The filling point is diametrically opposite to the ejection point while the plate surface cleaning point is about 36° past the ejection point in a counter-clockwise direction.

Thus, since there are six equally spaced plungers and compression chambers, the filling, ejection and cleaning operations occur at points of the plate periphery at the same time.

Due to receiving power drive from the same source, the cake forming machine and the aluminum strip moving apparatus begin to function simultaneously. The clockwise and counter-clockwise rotation respectively, of the left and right spur gears 23 provides a continuous action in the lowering of the aluminum strips within the magazine 16. The ends of the aluminum strips engage directly between the consecutive teeth of the revolving spur gears 23 and in this manner the aluminum strips are continuously fed to the endless conveyor. The aluminum strips are continuously fed forwardly by the endless conveyor, the ends of the strips when on the conveyor chain being in close contact as the product ejection point is approached.

By virtue of the relative speeds of the endless conveyor and the rotary plate, the conveyor travels sufficiently far between product cake ejections from the successive compression chambers in the rotating plate so that about one-half inch space is left between the adjacent cakes on the aluminum strips. The aluminum strips on receiving their quota of cakes push one another to the end of the machine where an operator removes the strips for transfer to a drying tunnel.

The layout of the cam is diagrammatically il-

lustrated in Fig. 19 of the drawings. At ejection point, the plunger as indicated in Fig. 19 has reached its highest vertical position. This position is maintained for 20° of the cycle.

Leaving ejection position after removal of the cake the plunger recedes to the level of the top of the plate 37 after a travel of 15° of the cycle. This brings the plunger almost to the metal scraper 72. During the next 55° of rotation of the plate 37 the plunger top remains level with the top surface of the plate 37 while the cleaning operation progresses. After a further travel of 45° of the cycle the plunger top has receded to its minimum vertical position, being at this time just beneath the first set of revolving mixing blades in the feeding and mixing chamber. During the next 75° of the cycle the depth of recession of the plunger remains unchanged while passing under the revolving mixing blades which have but little clearance between the blades and the revolving plate 37 causing the compression chamber to be tightly filled with the product due to the pressing action of the blades, all of which revolve in a clockwise direction and are set at a slight inclination. During the following 55° of the cycle the compression chamber leaves the mixing and feeding chamber and the plunger rises slightly further compressing the product in the compression chamber by pressing the product upwardly against the bottom of the portion 74. During the next 40° of the cycle the formed cake is elevated by the rise of the plunger which is lifted to its maximum elevation upon reaching a point 5° of the cycle from the ejection point. The remaining 5° of the cycle is traversed with the plunger at maximum elevation at the end of which the ejection point is reached where the ejector mechanism hereinafter described, removes the formed cake and places the same on one of the aluminum strips. This completes one cycle of the operation of the machine.

The cleaning device 73 comprises in its construction a shell 75 of sheet metal or other suitable material secured to the exterior of the segmental casing 53 and receiving a wiping element 76 of felt or other suitable material which wipes the surfaces after the same have been operated on by the scraper blade 72. The scraper blade 72 which presents its lower edge to the upper surfaces of the rotating plate 37 and the plunger is suitably secured to the shell or casing 75, as clearly illustrated in Fig. 9 of the drawings. The wiping element 76 is forced downwardly into close contact with the surfaces to be cleaned by spring actuated plunger rods 77 guided in a hinged top 78 of the shell 75 and carrying plates or heads 79 which bear against the upper surface of the wiping element. The plunger rods 77 and the plates 79 carried thereby are forced downwardly by coiled springs 80 disposed on two of the plunger rods and interposed between an inverted U-shaped member or yoke 81 and suitable projections of the said plunger rods. The cover 78 of the shell is hinged to the latter at 82 at one end thereof and is detachably retained in its closed position by a spring catch 83 located at the other end of the shell. The catch which may be of any desired construction, is mounted on the shell and engages over the adjacent edge of the cover. When the catch is disengaged from the cover the latter is adapted to be swung upwardly to carry the spring actuated plungers out of engagement with the wiping element. This will enable the wiping element after it has been

in use to be removed for cleaning or replacement by a fresh piece of felt or other material.

Following the removal of the product cake from the plunger top the latter will be gradually lowered so that when a plunger has traveled about 36° around the periphery of the rotating blade past the ejection point the top of the plunger has receded to the level of the top surface of the plate 37 within the compression chamber. At this point is located the said metal scraping edge 72 and just beyond the latter is located the surface cleaning device which by means of spring pressure holds the felt or other cleaning element in contact with the metal surface. The scraping edge 15 cleans the surface of coarse particles of product while the felt wiper finishes cleaning and also drying the surface of the rotating plate. To prevent difficulty in removal of product particles due to hardening or gumming, in practice, a thin 20 slow, flowing stream of distilled water will be continuously applied to the rotating plate surface just before the cleaning elements are reached and scrapings and drip will be caught in conveniently located troughs. In practice, the cylinders, 25 plungers and adjacent moving parts will be constructed of material such as nitaloy which does not require lubrication.

The ejector mechanism for transferring a formed cake 84 from the plunger to the aluminum strip 15 comprises in its construction a slidable and oscillatory ejector member 85 consisting substantially of a rectangular cap provided at the back with spaced arms 86 which are secured to spaced parallel arms 87 of a sleeve 88 having reduced portions 89 which are journaled in spaced bearings 90 of a carriage 91. The spaced bearings 90 are preferably provided with ball bearings 92, but any suitable anti-friction bearings may, of course, be employed and while the spaced rearwardly extending arms 86 of the ejector member are shown elevated to the arms of the sleeve the ejector member may be connected with the sleeve in any desired manner.

The journaling of the sleeve 88 in the projecting bearings 90 of the carriage permits the ejector element to have both an upward and downward swinging movement to place the cap of the ejector member over the formed cake 84 and the sliding of the carriage enables the ejector member to carry the cake from the plunger to the aluminum strip 15 and place the cake thereon. After the cake has been placed on the aluminum strip 15 the cap of the ejector member is raised from the cake by the means hereinafter fully described.

The carriage 91 consists of a rectangular sleeve slidable on the fixed horizontal shaft 93 extending outwardly from an attaching plate 94 and rigidly secured at its inner end. Plate 95 is rigidly attached to arm 93 and serves as a stop to limit the inward motion of carriage 91 and thereby causes cap 85 to register accurately in position over plungers 46 at the end of each ejection cycle. The fixed horizontal shaft 93 which forms a guide for the carriage is preferably provided in each of its faces with a longitudinal groove 96 forming spaced track portions 97 at each of the side faces of the shaft 93 to receive the carriage. The grooving of the faces of the shaft 93 reduces the friction incident to the sliding of the carriage 91 on the shaft. The attaching plate 94 is bolted or otherwise secured to a fixed portion of the machine, as clearly illustrated in Figs. 9 and 10 of the drawings, and the slidable carriage is provided at the bottom adjacent its inner end with a

depending stud 98 which is engaged by a horizontal arm 99 of a vertical sleeve 100 mounted on a vertical pivot 101. The stud is round and the terminal portion of the arm is provided with a segmental recess 102 which receives the stud. The arm 99 oscillates intermittently in a horizontal plane to reciprocate the slidable carriage 91. 5

The vertical pivot on which the sleeve is mounted is secured to and depends from a bracket 103 bolted or otherwise secured to a stationary portion of the machine and having an eye 104 in which the upper end of the pivot 101 is secured. The arm 99 extends from the upper portion of the sleeve and the latter is provided at its lower portion with a cam actuated arm 105 provided with a depending roller 106 arranged to be engaged by an annular series of cams 107 carried by the plate 37 and arranged at spaced points around the periphery of the same, as clearly illustrated in Fig. 17 of the drawings. The roller of the cam actuated arm is maintained in firm engagement with the cams by means of a coiled spring 108 disposed on the pivot 101 and having having its upper end connected to the cam actuated arm and its lower end connected with a sleeve 109. The sleeve 109 which is located adjacent the lower end of the arm is provided in its lower edge with a plurality of notches 110, one of which engages a projection 111 fixed to and 20 extending horizontally from the pivot 101. The tension of the spring 108 is adapted to be adjusted by rotating the sleeve 109 on the pivot 101 and engaging one of the notches 110 of the sleeve 109 with the said projection 111. The cams 107 are 25 oppositely tapered and when the roller 106 is engaged by and rides over a cam the arm is gradually moved outwardly by the cam until the peak of the movement is reached and then the arm 105 is moved inwardly through the action of the 30 coiled spring 108. This partially rotates the sleeve 100 first in one direction and then in the reverse direction, causing an oscillation of the carriage actuating arm 99 which reciprocates the carriage 91. This operation is repeated at 35 regular intervals as the cams 107 successively engage the arm 105.

The ejector element is equipped with a scraper 112 constituting the top of the cup-shaped portion of the ejector member and consisting of a 40 horizontal top portion and inclined walls 113 located at the front and sides of the scraper and having their lower edges engaging the inner faces of the front and side walls of the ejector element. The cup-shaped portion of the ejector member 55 consists of vertical front and side walls and the said arms 86 extend upwardly and rearwardly from the rear ends of the side walls at the upper portions thereof. The scraper is provided with a curved rearwardly and upwardly extending arm 60 114 provided at its upper rear end with spaced eyes 115 for the reception of a pintle 116 which hinges the arm 114 between spaced eyes 117 of an attaching plate 118 secured to the top of the slidable carriage. The hinged connection between the arm 114 and the carriage permits relative movement of the scraper and the ejector member during a portion of the oscillatory movement of the latter. The scraper is yieldably maintained in the slightly inclined position illustrated in Fig. 21 of the drawings, by means of a leaf spring 119 disposed longitudinally of the arm 114 at the lower face thereof and extending over the pintle 116 and having one end secured between the attaching plate 118 and the carriage. 70 75

The front portion of the spring 119 bears against the inner face of the arm 114. When the ejector member is elevated from the position shown in full lines in Fig. 21 of the drawings, to the position illustrated in dotted lines, the scraper and the ejector member have relative movement and the scraper which is approximately cup-shaped scrapes product crumbs from the inner faces of the walls of the ejector member, thoroughly 10 cleaning the latter.

The ejector member is provided at the front with a stop 120 to prevent the escape of scraper 112 from ejector cup 85 in an upward direction and consists of a plate secured to the ejector 15 member exteriorly of the front wall thereof and having an angularly bent upwardly and rearwardly projecting portion which in the downward movement of the ejector member engages the scraper 112 and maintains the same in position 20 for forming the top of the ejector member, as clearly illustrated in Fig. 20 of the drawings. Also the relative movement of the ejector member and scraper insures a positive and rapid discharge of the formed cake 84 from the ejector 25 member when the latter is lifted from the cake after carrying the same from the machine to the aluminum strip 15.

The ejector member is lowered from the elevated dotted line position illustrated in Fig. 21 30 of the drawings to the full line position shown in the said figure by means of a cam 121 which engages a finger 122 fixed to one end of a horizontal shaft 123 extending through and journaled in the sleeve 89 which is provided at one end with 35 an extension 124 projecting beyond the adjacent side bearing 90 of the carriage 91. The finger 122 is rigid with a collar 125 fixed to the inner end of the shaft 123. The collar 125 is also provided with a depending arm 126 carrying a horizontal 40 pin 127 which engages the ejector member. The horizontal pin 127 extends beneath one of the side bearings 90 of the carriage and projects into the plane of the adjacent arm 86 of the ejector member and is located beneath the said arm of the 45 ejector member and it forms a stop for limiting the downward movement of the ejector member and also is adapted to engage the ejector member for elevating the same after the ejector member has transferred the formed cake from the machine to the aluminum strip 15.

The cam operated finger 122 when free to move is actuated in a counter-clockwise direction by a coiled spring 128 disposed on the outer end portion of the shaft 123 and having one end engaged 50 with a projection 129 of the said shaft and its other end connected with a horizontal rod 130 mounted on the carriage at the outer end thereof and extending outwardly from the same at the inner end of the adjacent side bearing 90. When the shaft 123, which is extended beyond the sleeve 55 to receive the said spring 128, is rotated in a clockwise direction by the cam 121, the coiled spring 128 is tensioned and is adapted to rotate the said shaft 123 in a counter-clockwise direction to lift the ejector member from the aluminum strip and the cake.

The cam 121 is formed by an approximately triangular enlargement 131 of a cam plate 132 which is in the form of a bracket, being provided 60 at its inner end with an attaching flange 133 bolted or otherwise secured to the plate 94 which carries the fixed horizontal shaft 93. The cam plate 132 extends horizontally from the attaching plate 94 and is arched or curved transversely 65 above and like cam 131 is concentric with the

shaft 123, as clearly illustrated in Fig. 20 of the drawings. The triangular enlargement presents to the said finger 122 the cam edge 121 which is slightly concave and which is arranged at an angle, as clearly illustrated in Fig. 26 of the drawings, for causing the cam finger to move from the rear portion of the cam plate to the front portion thereof when the carriage moves inwardly on the shaft 93.

As the cam finger 122 is moved into clockwise 10 direction through the action of the cam 121 the spring 128 is tensioned and maintains the finger in tight engagement with the cam face. This movement of the finger also produces a partial rotation of the shaft 123 and a lowering of the 15 stop pin 127 and a consequent downward movement of the ejector member after finger 136 has passed the inner edge of stop 141. The ejector member is forced downwardly by a coiled spring 134 disposed on the extension 124 of the sleeve 20 and connected at one end to a collar 135 rigidly attached to shaft 123 by a set screw and at its other end to a finger 136 which is rigidly attached to extension 124 and consequently to arms 86 and 25 87.

As the cam control finger 122 approaches the inner end of the cam 121 it engages the free end 137 of a pivoted guide 138 and passes to the outer or front side of the same. The guide 138 which extends longitudinally of the cam plate is pivoted 30 at its outer end to the same by a screw 139 extending through the cam plate and projecting upwardly beyond the same, as clearly illustrated in Fig. 20 of the drawings. The pivoted guide 138 which operates in the nature of a latch is controlled by a coiled spring 140 disposed on the screw and connected at one end with the same and at the other end with a cam plate and adapted to maintain the free end of the pivoted guide normally in contact with the cam face or edge 121 35 of the cam plate. The free end of the pivoted guide 138 is beveled to fit the cam face and after the cam actuated finger 122 passes the pivoted guide the latter is snapped back by the spring 140 and presents a straight guiding edge or face 40 to the finger 122 which is held tightly against the guide by the tension of the spring 128 during the 45 succeeding outward movement of the carriage 91.

This outward movement of the carriage carries the formed cake from the machine to the aluminum strip 15 and when the cam actuated finger 122 passes beyond the outer pivoted end of the guide 138 the spring 128 acts instantly to lift the ejecting member from the aluminum strip and the cake and the finger 122 is swung upwardly and inwardly or rearwardly to a position in line with the inner end of the cam 121 which is provided with a straight guiding extension 141. This movement of the shaft 123 also carries the finger 136 to a position in line with a guideway 55 formed by spaced parallel flanges 143 and 144 rigid with and depending from an extension 145 of the cam plate. The extension 145 is located at the inner or rear longitudinal edge of the cam plate and extends longitudinally from the body 60 portion of the cam plate, as clearly illustrated in Figs. 25 and 26 of the drawings. The flanges 143 and 144 present smooth straight longitudinally disposed guiding faces to the finger 136. During the first portion of the inward movement of the carriage the finger 136 is guided by the flanges 143 and 144 and through the rigid connection of the finger with the sleeve 88 maintains the ejecting member in an elevated position. The collar 135 to which one end of the 70 75

spring 134 is connected is fixed to shaft 123. The spring tension between this collar and the finger 136 tends to force arm 86 against stop pin 127 except when finger 136 is restrained from rotation in a clockwise direction by projection 143. The finger 122 lifts the pivoted guide before the carriage reaches the limit of its inward movement. The straight guiding portion 141 of the cam and the front face of the flange 144 are provided with cushions 146 and 147 adapted to cushion the impact of the fingers 122 and 136 when the same are swung upwardly by the action of the coiled spring 128.

At the completion of the outward movement 15 of the carriage the finger 136 is carried to a position in line with the guideway 142 by coming in contact with pad surface 147 which limits its counter-clockwise rotational motion, so that when the carriage is moved inwardly it will function until it is carried beyond the inner ends of 20 the flanges 143 and 144 to the open space between the said flanges and the cam 121. This open space which is clearly illustrated in Fig. 26 of the drawings permits the finger 136 to become 25 inactive and to be rotated in a clockwise direction by the action of spring 134 thus bringing about the downward movement of the ejector cup 85, carried forwardly by the rotation of the sleeve during the downward movement of the 30 ejecting member.

When the product cake has been formed and the rotation of the plate 37 has brought the plunger top bearing the cake ready for ejection to discharge position, the ejector mechanism has 35 operated so that the cup of the ejector member has descended on the cake. After the cup of the ejector member has dropped into position due to the tension of the spring 134 the carriage to which the ejector member is attached travels 40 away from the cake forming machine towards the aluminum strip 15 due to the action of the cam surface on the periphery of the rotating plate 37 which cam engages the roller 106 of the arm 105. This movement swings the arm 99 and 45 actuates the carriage. As the carriage 91 moves along the shaft 92 the cup of the ejector member is held in the solid line position shown in Fig. 21 by contact of the cam finger 122 with the pivoted guide 138 against the tension of the spring 50 128. At this time the finger 136 is inactive. When the finger 122 reaches the end of the pivoted guide 138 the cup of the ejector member has transferred the product cake from the plunger top to the center of the aluminum strip 15.

The cup is then instantly raised vertically 55 from the cake by a counter-clockwise rotation of the sleeve 88 due to upward pressure of the stop pin 127 on the bottom portion of the cup of the ejector member as the cam finger 122 rotates in a counter-clockwise direction due to 60 the tension of the spring 128 following the release of the cam finger 122 from the pivoted guide 138. As the cup of the ejector member rises clean ejection from the cup is insured by 65 scraping contact of the cleaner or scraper element 112 with the walls of the cup. Lag in the raising of the scraper or cleaner element with respect to the rise of the cup of the ejector member is due to the tension of the leaf spring 119. 70 With the rise of the cup the finger 136 which is also rigidly attached to the sleeve 88 has revolved through an equal angle in a counter-clockwise direction. Thus, as the carriage 91 reverses its direction of travel practically simultaneously with the counter-clockwise movement 75

of the finger 136 the latter moves with the rider entering the space between the guide flanges 143 and 144 sliding on the flange 143 which acts as a guide. This action is due to the fact that as the finger 136 approaches the guide the spring 5 128 is decreasing in tension. When the end of the guide flange 143 has been reached the spring 134 causes the finger to revolve clockwise to its inactive position, thus causing the entire ejector cup assembly comprising finger 136, shell 88, 10 arms 86 and 87 to rotate about shaft 123 until arm 86 comes to rest against stop pin 127. Throughout the entire inward motion of the carriage 91 spring 128 forces the cam actuated finger 122 in close contact with the cam surface 15 121, the finger 122 entering on the curved portion of the said cam surface 121, winding spring 123 preparatory to the next cycle.

As the carriage 91 travels farther on the shaft 93 and the cam actuated finger 122 approaches 20 the end of the cam surface 121, the tension of the spring 128 increases and the cup-shaped portion of the ejector member continues to descend. When the end of the cam surface 121 is reached 25 pressure of the finger 122 forces the pivoted guide 25 to yield against the pressure of the spring 140. The finger 122 thus reaches the outside surface of 30 the pivoted guide 138, the latter being returned to its place by the spring 140. At this point the cup of the ejector member has descended completely on the cake product on top of the plunger at the discharge or ejection point.

The operation of the machine in the manufacture of gelatin dessert cakes or tablets will now be described: The material which, as has been 35 previously pointed out, is a slightly moist mixture of sugar, gelatin, flavoring, color, and the like, in the condition of a slightly moist friable powder, is placed in hopper 64. Agitator 68 causes the material to flow freely past the regulating valve 66 40 down the slide 65 into the hopper opening 67. While the material is in hopper space 52, it is constantly agitated to prevent caking and arching over openings 45. Table 37 shown in Figure 14, 45 rotating in the direction shown by the arrow causes cake forming pockets 45 to pass under the hopper area 52. When the pockets enter the hopper area, the plungers 46 are in their lowermost position and it will be seen, therefore, that pocket 45 at this point has the maximum volume. 50

Due to the action of gravity and the agitating effect of rotating blades 56, the material is caused to drop into pockets 45 until the pockets are entirely filled. An overcharge of material is loosely packed into the pockets. As the table continues 55 to move and the pockets are carried further around under the hopper and as they approach the exit side of the hopper, plungers 46 are caused to move gradually upward reducing the volume of pockets 45 and expelling some of the excess material and at the same time compressing the material remaining in the pockets against the mass of material contained above in the hopper. This upward movement of the plungers continues until it has reached the point, just previous to the time when the pocket passes from under the hopper opening, where the volume of material in pocket 45 is the required amount for the desired finished product. 60 65

The exact amount of the upward motion of the plunger is adjustable and is controlled, as shown in Figure 19, by the left-hand portion of the cam marked "Compression." The continued rotation of the table carries pockets 45 from under the open area of the hopper and brings them under 70 75

the solid area, which solid area is in effect a plate very closely adjacent to the surface of moving table 37.

While the pockets are passed under the solid plate, plungers 46 are given a further slight upward motion to compress the contents of pockets 45 to the desired thickness and to produce a smooth top surface on the cake. The continued rotation of the table causes the pockets containing the compressed material to be carried out into the open space above the table in which area the material, which has now been formed into cakes of desired size and shape, may be transferred to suitable trays 15. As soon as pockets 45 have passed the solid region 14 of the hopper, plungers 46 commence to rise. This action of the plungers is brought about by the sloping approach to the discharge portion of the cam, as is shown in Figure 19 in the 40° section following the compression portion.

At the end of the rising movement of the plungers, the formed and pressed cake 84 is resting on the top of plunger 46 which is slightly higher than the top surface of tray 15. Under these conditions it is possible to slide the cake 84 from plunger 46 to tray 15, the transfer being effected by the action of the ejector mechanism shown in Figure 20. Ejector cup 85 is held in the position shown in Figure 20 in which it is centered over plunger 46. It will be noted that the end of ejector cup 85 adjacent its pivot is open. With the ejector cup in this position the cake 84 may be swept into the confines of the three walls of the ejector cup by the motion of plungers 46 with the table. As soon as the cake has reached the position in Figure 20 in which the front end of the cake has come in contact with the front end of ejector cup 85, its motion with plunger 46 is abruptly stopped and the bottom of cake 84 commences to slide on the top surface of plunger 46. At this point the motion of the cake 84 is under the control of the ejector mechanism and at this instant the ejector cup 85 starts to move in the direction of tray 15 carrying with it cake 84, this motion being brought about by cams 107. The distance between plunger 46 and tray 15 is comparatively short so that as the cake moves from the plunger to the tray it is at all times resting with a large part of its surface either on plunger 46 or on both the plunger and the tray or entirely on the tray. In this manner the gap between the two supports is bridged by the cake itself.

As the cake 84 is swept from plunger 46 by the straight line motion of ejector cup 85, it continues to move, first with a uniform acceleration and then with a uniform deceleration until it has reached a point centrally positioned over tray 15, after which its further motion is controlled by the motion of tray 15. At this instant, the ejector cup 85 is caused to swing rapidly upward about its pivot shaft 123. This swinging action takes place when arm 122 passes beyond the edge of cam 138.

As the ejector cup swings upward about its pivot, it leaves cake 84 resting centrally on tray 15. The motion of tray 15 in the direction indicated by the arrows in Figure 20 carries the cake away from the machine and presents an unfilled portion of tray 15 to receive the next cake.

As soon as the ejector mechanism has moved so as to release the cake on tray 15 by the upward motion of cup 85, it is ready to be returned to its initial position to receive the next cake.

This return motion is controlled by spring 108 which causes roller 106 to follow cams 107.

As the entire ejector assembly moves inwardly along bar 93, arm 122 moves along cam surface 121 and eventually opens latch 138 and assumes a position on the outside of this latch. This motion of the ejector assembly winds spring 128.

In the meantime, ejector cup 85 is held in its up position so that it will not interfere with cake 84 which is now resting on tray 15 and moving with it by arm 136 which is restrained from clockwise rotation by plate 143. As soon as ejector carriage 91 has moved far enough on its inward travel along bar 93 to bring arm 136 beyond the innermost edge of plate 143, spring 134 causes the ejector cup 85 together with its controlling arm 136 to rotate in a clockwise direction until its motion is stopped by contact with projecting pin 127 which is integral with arm 122. The ejector is now in its initial position and ready to receive the next cake.

Scaper 112 is provided to remove any particles of the material from the interior walls of cup 85 so that clean smooth surfaces are constantly presented to each new cake.

Small quantities of material may adhere to the top surface of plungers 46 and it is desirable to remove this small quantity of material at each cycle. To bring about this result scraper 72 and felt wiper 76 are provided. These devices contact the top surfaces of the table and the tops of the plungers 46, at the time that the surfaces of the plungers are exactly flush with the top surface of the table.

It has been found desirable in practice to provide a small, steady stream of water playing upon the surface of the table 37 immediately preceding the scraper blade 72. This scraper blade, which consists of a piece of brass plate to which is attached a piece of soft rubber, acts as a squeegee and prevents any substantial quantity of water from being carried beyond it. The excess water flows over the edge of the table to be gathered into a suitable receptacle.

The rotation of table 37 is continuous and uniform as is the movement of conveyor chain 10 which carries trays 15. As each tray 15 is completely filled with cakes and is ready to be discharged from the machine, another tray enters to take its place. The surface presented by these trays is continuous and unbroken since each succeeding tray butts snugly against the end of the preceding one. The length of trays and the timing of the machinery is arranged so that the same number of cakes is deposited on each tray in such a manner that no cake will come at a point over the joint between any two trays.

What is claimed is:

1. A machine of the class described including a rotating body provided with vertical compression chambers, vertically movable plungers operating in the compression chambers for compressing material therein, a stationary casing located above the rotating body, a plurality of feeding devices located within the casing having means for packing material in the compression chambers, gearing connecting the feeding devices, a gear fixed to the rotating body, and a gear meshing with the fixed gear and connected with the said gearing whereby the feeding devices are operated by the rotating body.

2. A machine of the class described including a rotating body having vertical compression chambers, vertically movable plungers operating in the compression chambers, a stationary casing locat-

ed above the rotating body, a plurality of rotating devices mounted within the stationary casing and having means for feeding material to and packing the same in the compression chambers, 5 gearing connecting the said rotating devices, a horizontal internal gear fixed to and rotating with the body, and a pinion meshing with and rotated by the internal gear and connected with the said gearing for transmitting motion 10 from the rotating body to the said rotating devices.

3. A machine of the class described including a rotating body having vertical compression chambers, vertically movable plungers operating in the 15 compression chambers, a stationary casing located above the rotating body, a plurality of rotating devices mounted within the stationary casing and having means for feeding material to and packing the same in the compression chambers, 20 and chain gear drives connecting the rotating devices for rotating said devices in the same direction.

4. A machine of the class described including a rotating body provided with vertical compression 25 chambers, vertically movable plungers operating in the compression chambers, a stationary casing located above the rotating body, a plurality of vertical shafts mounted within the said casing and provided with blades for feeding and packing material within the compression chambers, 30 chain drive gearing connecting the vertical shafts for rotating the said shafts in the same direction, an internal horizontal gear fixed to the rotating body, and a pinion meshing with the internal gear and connecting with the chain drive 35 gearing for transmitting motion from the rotary body to the said vertical shafts.

5. A machine of the class described including a rotating body having vertical compression 40 chambers, vertically movable plungers operating in the compression chambers to compress material and to elevate the compressed material above the rotating body, means for removing the compressed material from the machine, and a cleaning device including a stationary shell, a wiping element mounted in the shell and arranged to wipe the surface of the rotating body after the removal of the compressed material, and means 45 yieldably maintaining the wiping element in tight engagement with the rotating body.

6. A machine of the class described including a rotating body having vertical compression 50 chambers, vertically movable plungers operating in the compression chambers to compress material and to elevate the compressed material above the rotating body, means for removing the compressed material from the machine, a cleaning device including a stationary shell, a wiping element mounted on the shell and arranged to wipe the surface of the rotating body after the removal of the compressed material, a top for the shell removable from over the same, and a spring 55 actuated plunger carried by the top for yieldably maintaining the wiping element in engagement with the rotating body.

7. A machine of the class described including a rotating body provided with vertical compression chambers, vertically movable plungers operating 60 in the compression chambers to compress material therein and to elevate the compressed material above the rotating body, an ejector member, and means for moving the ejector member upwardly, downwardly and horizontally to arrange the ejector member over the compressed 65

material and to remove the material from the machine.

8. A machine of the class described including a rotating body provided with vertical compression chambers, vertically movable plungers operating in the compression chambers to compress material therein and to elevate the compressed material above the rotating body, an ejector member, and means for moving the ejector member upwardly and downwardly and for reciprocating the ejector member whereby the ejector member is carried to a position over the compressed material and is caused to remove the material from the machine. 10

9. A machine of the class described including a rotating body provided with spaced cams and having vertical compression chambers, vertically movable plungers operating in the chambers to compress material therein and to elevate the compressed material above the rotating body, a reciprocating carriage, an oscillatory member intermittently actuated by the said cams and connected with the carriage for reciprocating the same, an ejector member mounted on the carriage, and means automatically operated by the reciprocation of the carriage for raising and lowering the ejector member whereby the ejector member is carried to a position over the compressed material and is caused to remove the material from the machine. 15 20 25 30

10. A machine of the class described including a rotating body having vertical compression chambers, vertically movable plungers operating in the compression chambers to compress material therein and to elevate the compressed material above the rotating body, a plurality of spaced cams carried by the rotating body, a fixed vertical pivot, a sleeve mounted on the pivot and having upper and lower arms, the lower arm being arranged in the path of and adapted to be actuated by the said cams, a spring mounted on the pivot and connected with the sleeve for moving the said lower arm inwardly and for maintaining the same in contact with the said cams, a reciprocating carriage connected with and actuated by the upper arm of the sleeve, an ejector member hinged to the carriage, and means automatically operated by the reciprocation of the carriage for raising and lowering the ejector member whereby the said ejector member is placed over the compressed material and is caused to remove the same from the machine. 35 40 45 50 55

11. A machine of the class described including a rotating body provided with vertical compression chambers, vertically reciprocating plungers operating in the compression chambers to compress material and elevate the same above the rotating body, a horizontally reciprocating carriage intermittently actuated by the rotating body, a hinged ejector member mounted on the carriage and provided with a cup-shaped portion, and means automatically operated by the reciprocation of the carriage for raising and lowering the ejector member to place the cup-shaped portion over the compressed material and to cause the ejector member to remove the material from the machine. 60 65 70

12. A machine of the class described including a rotating body provided with vertical compression chambers, vertically reciprocating plungers operating in the compression chambers to compress material and elevate the same above the rotating body, a horizontally reciprocating carriage intermittently actuated by the rotating body, a hinged ejector member mounted on the 75

carriage and provided with a cup-shaped portion, and means automatically operated by the reciprocation of the carriage for raising and lowering the ejector member to place the cup-shaped portion over the compressed material and to cause the ejector member to remove the material from the machine, said ejector member being provided at the top of the cup-shaped portion with a relatively movable scraper arranged to discharge the compressed material from the cup-shaped portion and to clean the walls thereof.

13. A machine of the class described including a rotating body provided with vertical compression chambers, vertically reciprocating plungers operating in the compression chambers to compress material and elevate the same above the rotating body, a horizontally reciprocating carriage intermittently actuated by the rotating body, an ejector member hinged to the carriage and having a cup-shaped portion provided with a relatively movable top adapted to scrape and clean the walls of the cup-shaped portion and cause the material to be discharged therefrom, yieldable means connecting the relatively movable portion of the cup-shaped portion with the carriage, and means automatically actuated by the carriage for raising and lowering the ejector member to place the cup-shaped portion over the compressed material and remove the same from the machine.

14. A machine of the class described including a rotating body provided with vertical compression chambers, vertically reciprocating plungers

operating in the compression chambers to compress material and elevate the same above the rotating body, a horizontally reciprocating carriage intermittently actuated by the rotating body, an ejector member hinged to the carriage and provided with a cup-shaped portion, a top for the cup-shaped portion yieldably connected with the carriage and having a limited movement independently of the said cup-shaped portion whereby it is adapted to scrape and clean the walls of the cup-shaped portion and discharge the compressed material from the cup-shaped portion, and means automatically operated by the reciprocation of the carriage for raising and lowering the ejector member to place the same over the compressed material and cause the latter to be removed from the machine.

15. A machine of the class described including a rotary body having compression chambers, vertically movable plungers operating in the compression chambers to compress material into cakes and elevate the same above the compression chambers, ejector mechanism including a fixed horizontal shaft, a carriage slideable on the shaft, an ejector member hinged to the carriage and movable downwardly to engage the cakes and also movable horizontally by the carriage to discharge the cakes from the machine, means actuated by the rotary body for intermittently reciprocating the carriage, and means automatically actuated by the carriage to raise and lower the ejector member.

CHARLES T. WALTER.
JOSEPH BECH.
